UNITED STATES PATENT OFFICE

BRYAN HOWARD, OF AUSTIN, TEXAS

BLOTTING PAD

Application filed October 9, 1929. Serial No. 398,398.

This invention relates to blotting pads and more particularly to devices of this character which are adapted to be mounted for use on the wrist of an operator in such a manner that the same may be conveniently brought into engagement with the work to be blotted.

An important object of the invention is to provide, in a manner as hereinafter set forth, a blotting pad of the aforementioned character wherein a sheet of blotting paper is securely held in position on a supporting base in such a manner that the same may be expeditiously detached therefrom for the purpose of mounting a new sheet thereon.

Another object of the invention is to provide a blotting pad of the character set forth wherein the base or support is adapted to fit the wrist of the operator and is further provided with adjustable means for securing the same thereto.

Other objects of the invention are to provide a blotting pad which will be simple in construction, strong, durable, efficient in its use and which may be manufactured at low cost.

Other objects and advantages of the invention will become apparent from a study of the following description, taken in connection with the accompanying drawings, wherein like characters of reference designate corresponding parts throughout the several views, and wherein:

Figure 1 is a perspective view of the blotting pad attached to the wrist of an operator.

Figure 2 is a front elevation thereof.

Figure 3 is a vertical cross-section taken approximately on the line 3-3 of Figure 2.

Figure 4 is a top plan view, partly broken away in horizontal section, of a blotting pad supporting base.

Figure 5 is a view of the sheet of blotting paper to be mounted on the supporting base.

Figure 6 is a detail view in top plan showing the spring clamp which secures the blotting paper on the supporting base.

Referring to the drawings in detail, the reference character 1 designates a flat support of substantially rectangular configuration, the front and rear ends of which are straight and the side marginal portions of

which are arcuate. As seen most clearly in Figure 4 of the drawings, a channel or groove 2 extends around the marginal edges of the support 1 on its front and rear edges and on one side edge and the ends of said groove merge with recesses 3 adjacent the ungrooved side edges of the support. The walls of the recesses 3 which merge with the groove 2 are rounded as at 4.

A sheet of blotting paper 5 of a shape conforming substantially to the support 1 is mounted on the lower flat surface of said support and is provided with marginal extensions or flaps 6 which are bent upwardly and extend over the adjacent portion of the groove 2 on the front and rear edges of the support 1. A substantially U-shaped resilient clamp 7 is then mounted in the groove 2 over the flaps or extensions 6 and said flaps are thus pressed firmly into and retained in said groove, as seen in Figure 3. The free ends of the clamp 7 are provided with in-turned rounded hook portions 8 for insertion in the recesses 3 at the ends of the groove 2 and said hook portions conform substantially to the rounded walls 4 of the recesses.

The rounded walls 4 of the recesses 3 cooperate with the rounded hook portions 8 to draw and seat the clamp 7 in the groove 2 by reason of the resiliency of the clamp.

The upper face of the support 1 is provided with a concavity 9 extending from the front to the rear thereof for the reception of the operator's wrist. This concavity 9 is spaced inwardly from the marginal sides of the support 1 and staples 10 are anchored in the upper face of said support between said concavity and the marginal side edges. A wrist strap 11 is secured to one of the staples 10 through the medium of the loop and snap fastener 12 and the opposite end of said strap is adjustably secured to the other staple through the medium of the loop and buckle 13. The device is thus rendered adjustable for fitting wrists of different sizes. For this purpose the staples 10 may be mounted at any desired point on the support.

It is to be understood, of course, that the support 1 may be formed of any desired material such as vulcanite, celluloid or wood,

and it is to be further understood that any desired securing means may be associated therewith for the purpose of mounting the same on the operator's wrist.

It is believed that the many advantages 5 of a blotting pad constructed in accordance with this invention will be readily understood, and although the preferred embodiment of the invention is as illustrated and described, it is to be understood that changes 10 in the details of construction may be had which will fall within the scope of the invention as claimed.

What is claimed is:—

15 A blotter holder of the character described comprising an elongated, flat, substantially rectangular plate for supporting the blotter and having communicating grooves in one end and on its front and rear walls, the grooves in the front and rear walls adapted 20 for the reception of certain of the marginal portions of the blotter, the front and rear walls being further provided with sockets adjacent the other end of the plate having curved side walls and communicating with 25 the adjacent ends of the grooves, a substantially U-shaped resilient clamp detachably mounted in the grooves and operatively engaged with the blotter, integral, inwardly curved hooks on the ends of the clamp engageable with the adjacent curved side walls 30 of the sockets for seating the clamp in the grooves, and means for mounting the plate on a persons wrist.

35 In testimony whereof I affix my signature.
BRYAN HOWARD.
